(57) **CLAIM**

The ornamental design for a display screen or portion thereof with an animated graphical user interface, as shown and described.

DESCRIPTION

A portion of the disclosure of this patent document contains material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

FIG. 1 is a front view of a display screen or portion thereof with an animated graphical user interface, showing a first image in a sequence of a first embodiment according to the new design;

FIG. 2 is a second image thereof;

FIG. 3 is a third image thereof;

FIG. 4 is a fourth image thereof;

FIG. 5 is a front view of a display screen or portion thereof with an animated graphical user interface, showing a first image in a sequence of a second embodiment according to the new design;

FIG. 6 is a second image thereof;

FIG. 7 is a third image thereof; and,

FIG. 8 is a fourth image thereof.

The outmost broken line rectangle shows a display screen or portion thereof which forms no part of the claimed design. All other broken lines showing portions of the animated graphical user interface show environment only and form no part of the claimed design.

The appearance of the animated images sequentially transitions between FIGS. 1-4 and FIGS. 5-8. The process or period in which one image transitions to another forms no part of the claimed design.
